UNITED STATES PATENT OFFICE

FERDINAND F. WAECHTER, OF PHILADELPHIA, PENNSYLVANIA, ASSIGNOR TO LINK-BELT COMPANY, A CORPORATION OF ILLINOIS

TROLLEY DEVICE

Application filed December 22, 1930. Serial No. 504,027.

This invention is concerned with load carrying trolley devices, and its particular object is to avoid the troublesome and costly results of loads acting at an angle to the vertical center line of a trolley device.

The problem involved exists in many different situations, of which the one here presented may be regarded as typical. In material handling systems of the general type

10 herein shown, the problem is one of long standing, on which much effort has been expended, and for which no adequate solution has thus far been presented. Such systems usually involve a trolley beam and a trolley follower consisting of rollers supported by the beam and mounted in a frame from which the load is suspended. When the load acts at 15 an angle to the vertical center line of the trolley beam, forces are set up which tend to severely distort the beam and impair its anchorage, thus leading to costly repairs or replacement. These forces also impose abnormal strains on the trolley follower which may result in serious damage.

25 In the drawings,

Figure 1 is a plan view illustrating the general layout of the particular system to be herein considered.

Figure 2 is a sectional view along line 2-2 30 of Figure 1.

Figure 3 is a sectional view illustrating the objectionable condition which the present invention is designed to correct.

Figure 4 is a view in side elevation showing 35 the application of the present invention.

Figure 5 is a sectional view, also illustrating the application of the invention.

Figure 6 is a view similar to Figure 5, but illustrating a modified form of the invention.

40 The particular material handling system in connection with which the present invention will be described may consist of several material receiving bins or pockets, a trolley beam above the pockets, and means for hoisting material from a point laterally offset with respect to the vertical plane of the trolley beam and then conveying the same longitudinally of the beam and depositing it in any one of the several pockets. A general illustration of such a system is found in Figures 1

and 2, wherein the several bins or pockets *a* are indicated at 1, 2 is the overhead trolley beam, 3 is the hoist cable, 4 is the hoist bucket, 5 is the inclined track on which the bucket travels, and 6 is a means for loading the 55 bucket. The cable load is carried by trolley beam 2 through the medium of a trolley follower and other means which will now be described.

Referring to Figures 3, 4 and 5, it will be 60 seen that the trolley follower consists of two substantially U shaped frames 7, in each of which is mounted a pair of rollers 8 designed to run on the lower flange of the I section trolley beam 2. Pivotedly suspended from 65 each of the frames 7 is a sheave carrying yoke 9 in which sheaves 10 are journaled. Yokes 9 are rigidly secured together by tie plates 11. The hoist rope 3 extends over sheaves 10 and around a sheave 12 which is journaled in the 70 upper portion of bucket 4. This arrangement of sheaves and hoist rope serves to raise and lower the bucket in a manner well understood in this art. Other cables or ropes 13 serve to move the bucket along the trolley 75 beam.

The bucket 4 is provided with pairs of rollers 14 on opposite sides, which engage track 5, and which are so positioned as to maintain the bucket in an upright position during its 80 travel along the track.

It will be understood that the design of the bucket supporting track 5 will vary according to the conditions peculiar to each installation. The path of travel of the bucket 85 may be either straight or broken, and at a greater or lesser angle than shown. In any case, the problem remains so long as the point from which the material is to be hoisted is laterally offset with respect to the vertical 90 plane of the trolley beam.

Considering now the operation of the system shown, and referring particularly to Figure 2, it will be noted that with the bucket in the position shown, the hoist cable 3 extends at a considerable angle to the vertical plane of the trolley beam. This angle progressively diminishes as the bucket moves up the inclined track. However, during the entire hoisting operation up to the point 100

where the cable coincides with the vertical plane of the beam, there is a direct off-center load on the trolley follower tending to shift the follower laterally with respect to the beam and to severely distort the latter. This condition is illustrated in Figure 3, from which it will be observed that substantially the entire load is imposed upon the left trolley roller and the outer left hand edge of the lower flange of the beam. This condition results in distortion of the flange and web of the beam and also tends to impair its anchorage.

The conditions described above are well known, as they have existed in this and similar situations for a long time. Many means have been suggested and tried to meet these conditions, but none seems to have withstood the test of practical application. The present invention presents a tried and satisfactory solution to this problem. Referring to Figures 4 and 5, there is shown a guide beam 14 of right angle section, supported by a pair of brackets 15. This beam is positioned parallel to and spaced laterally from the trolley beam 2. To each trolley frame 7 there is secured a short angle iron 16 whose inside vertical and horizontal surfaces are provided with contact shoes 17 designed for engagement with the vertical and horizontal faces, respectively, of guide beam 14. The shoes 17 are secured to angle irons 16 by means of suitable bolts and they may be adjusted with respect to angle irons 16 by the interposition of shims, as shown. Both the vertical and horizontal faces of guide beam 14 are beveled at opposite ends so that the contact shoes 17 readily move onto the guide beam when the trolley follower moves into the zone of the latter. In this connection, it will be noted that the guide beam is relatively short and is positioned substantially central with respect to the inclined track 5, so that it is effective only during hoisting of the bucket up the inclined track.

The shoes 17 are so adjusted as to have light contact with the guide beam 14 when the load on the trolley follower is in vertical alignment with the trolley beam. Hence, when the load is acting at an angle to the plane of the trolley beam, as when hoisting a filled bucket from the bottom of inclined track 5, the resulting lateral and upward thrust of the trolley follower is transmitted directly to guide beam 14, thus relieving the trolley beam of torsional strain, and maintaining the trolley follower in normal position with all rollers in effective engagement with the beam.

It is to be understood that the actual construction of the parts constituting the invention may be varied without materially affecting the results. For example, a single contact shoe would be entirely effective, and this could be either the vertical or horizontal

shoe. Also, the means for adjusting the shoe or shoes, the means for securing them to the trolley frames, and the design and positioning of the guide beam, all may be varied in proper relation without destroying the benefits of the invention.

In Figure 6 there is shown a modification of the invention, wherein each pair of angularly related contact shoes 17 of the preceding figures is replaced by a single angularly disposed contact member 18, designed for cooperation with a guide beam 19 having an angularly disposed contact surface. Thus, the cooperating inclined surfaces of contact member 18 and guide beam 19 serve to take both the lateral and upward thrusts of the trolley follower. Obviously, means of adjustment may be provided in this form of the invention if desired.

Although the invention is relatively simple as regards construction, the results which it produces are of considerable economic value. These results may be secured in the manner herein set forth in any situation involving substantially the same problem as here presented, as will be readily appreciated.

Claims:

1. In a material handling system, the combination of a trolley beam positioned in a fixed plane, a trolley follower adapted to travel longitudinally on said beam, loading means located at a point laterally offset with respect to the plane of the trolley beam, a hoist bucket adapted to be loaded at said point and to be moved along an inclined path from said point to a position directly beneath said trolley beam, means connecting said bucket and trolley follower for so moving said bucket, and means for preventing the imposition of torsional strain on said trolley beam due to the angularity of the load acting on said trolley follower.

2. The combination with a trolley beam positioned in a fixed plane, a trolley follower, and a load connected to said follower and acting in a plane substantially at right angles to the plane of said beam, of means for preventing the imposition of torsional strain on said beam due to the angularity of the load acting on said follower.

3. The combination with a trolley beam positioned in a fixed plane, a trolley follower, and a load connected to said follower and acting in a plane at an angle to the plane of said beam, of means for preventing torsional movement of said follower due to the angularity of the load acting thereon, said means consisting of an abutment positioned adjacent said beam and adapted to be engaged by said follower.

4. The combination set forth in claim 3, characterized in that said means consists of cooperating abutments, one relatively stationary and the other carried by said follower.

5. The combination set forth in claim 3 characterized in that said means consists of an adjustable abutment on said follower and a cooperating stationary abutment.
6. The combination with a trolley beam arranged in a substantially vertical plane, a trolley follower adapted to be moved longitudinally thereon, a load carrying device connected to said follower and adapted to be elevated along an inclined path from a lower point laterally offset with respect to the vertical plane of the trolley beam, of an adjustable abutment carried by said follower and a cooperating stationary abutment.
10. 7. The combination with a trolley beam arranged in a substantially vertical plane, a trolley follower adapted to be moved longitudinally thereon, a load carrying device connected to said follower and adapted to be elevated along an inclined path from a lower point laterally offset with respect to the vertical plane of the trolley beam, of a stationary abutment positioned adjacent and parallel to said beam and having angularly related 20 contact surfaces, and cooperating abutments carried by said follower and adapted to engage said surfaces.
15. 8. In a material handling system, the combination of a plurality of material receptacles, a trolley beam positioned above said receptacles, a trolley follower adapted to be moved longitudinally on said beam, an inclined track extending from beneath said beam to a point laterally offset with respect thereto, load carrying means operatively connected to said follower and adapted to be moved from the lower end of said track to a point beneath said beam and then longitudinally of said beam into operative relation to any one of 25 said receptacles, and an abutment positioned adjacent said beam and adapted to be engaged by said follower when the latter is in hoisting position to relieve said beam and follower of torsional strain due to the angularity of 30 the load acting on the latter.

Signed at Philadelphia, Pa., this 16th day of December, 1930.

FERDINAND F. WAECHTER.
